UNITED STATES PATENT OFFICE.

JOHN ALLEN HEANY, OF NEW YORK, N. Y., ASSIGNOR TO HEANY LABORATORIES, INC., OF NEW HAVEN, CONNECTICUT, A CORPORATION OF CONNECTICUT.

ELECTRIC-ARC LAMP.

Application filed June 11, 1917; Serial No. 174,101. Renewed June 28, 1925.

The invention relates to electric arc lamps operating on very low wattages and at the ordinary commercial voltages, and maintaining high efficiencies even in the smaller sizes 5 ranging as low as ten or fifteen candle power. To this end, the invention comprises a lamp, involving a container or envelope, preferably adapted for connection in the ordinary incandescent lamp socket and containing an inert gas, preferably under diminished pressure, and two electrodes, between which an arc is established and maintained, connected to suitable lead wires, at least one of which electrodes comprises a rod 10 or tube of highly refractory oxide provided with a coil or filament of highly refractory metallic wire wound thereon or imbedded therein, said electrode having a terminal formed of a second class conductor, which 15 becomes conductive when heated, and to which the refractory wire aforesaid is connected, said electrodes being associated with a shunt or by-pass normally bridging the terminals, which shunt is adapted to be 20 opened or broken, by suitable means, preferably a thermostat, which operates when sufficient heat is developed, to separate the electrodes to proper arcing distance and also to move the separable contacts of the shunt 25 30 apart.

In the accompanying drawings,

Fig. 1 illustrates a lamp involving the invention.

Fig. 2 is a fragmentary view showing a 35 modification thereof.

Referring to the drawings, 1 indicates the globe or bulb of the lamp, which is preferably in the form usually employed in incandescent filament lamps, adapted for the usual 40 socket connection, which bulb is exhausted of air and supplied with an inert gas, such as nitrogen, argon, or the like, preferably under diminished pressure. The bulb is provided with the usual form of glass neck 1' in which are mounted the usual lead wires, to one of which is connected a conducting and supporting wire 2, to the lower end of which is attached one of the electrodes by means of a clamp 2' attached to the lower 45 end of the supporting wire 2. Said electrode comprises a rod or tube 3 of highly refractory material, such, for example, as thoria or zirconia, which electrode is non-conducting at ordinary temperature of the lamp, but

which becomes conductive at the temperature 55 of incandescence. Associated with said electrode 3 is a wire helix 7 of highly refractory metal, such as tungsten, tungsten alloy or the like, which helix is either closely wound around the element 3 or imbedded therein, 60 and which is connected at one end to the supporting wire 2 and at the other end to a ball or knob-like terminal 4, which is formed of material constituting a second class conductor, which is non-conducting at normal temperatures, but becomes conductive when highly heated. This terminal may advantageously be composed of a mixture of refractory oxides, such, for example, as thoria and 65 yttria or zirconia and yttria. The electrode 3 is formed by mixing powdered oxides with a dissipating binder, moulding it into the desired form and then driving off the binder by heat. The terminal 4 is formed in much the same way but is made with a depression of 70 the same cross-section as the electrode. The terminal is then placed over the electrode and fused thereto in an electric arc, the end of the electrode being inserted in the depression.

The inner end of the helix 7 is also connected by a wire 10 having on its end a terminal 12 which coacts with a similar terminal 13 connected to a wire 11, which latter in turn is connected to the opposite electrode, 75 between which and the electrode heretofore described the arc is maintained. Said opposite electrode may be formed like that first described, to wit, a tube or rod 5 of refractory non-conducting oxide with a terminal 80 of second class conducting material 6 and a highly refractory metallic helix 7' associated therewith and connected at its inner end to the terminal 6 and to the wire 11.

This electrode is preferably supported by 85 means of a clamp 16 carried by a stiff wire 17 which is fused to the lower end of a thermostat 8, the upper end of which is cemented in the glass neck 1' and connected by a suitable lead 9 to the other terminal of the lamp.

Instead of constructing the two electrodes of similar materials, one of them may be formed of a highly refractory metal, such as tungsten or tungsten alloy, in which case, the electrode would be made of proper form and supported from one or the other of the conductors, preferably the thermostat 8.

The operation of the lamp as described is

as follows: Current enters by way of lead 2, passes through the refractory metal helix 7 to wire 10, contacts 12 and 13, wire 11, helix 7', thermostat 8, lead 9, back to the other terminal of the lamp. The immediate effect of the current is to heat the wire helixes 7 and 7' to a high temperature to produce incandescence, which in turn raises the temperature of the refractory oxide supports 3 and 5, and also raises the temperature of the terminals 4 and 6 sufficiently to render the same first class conductors. The heating of these elements ionizes the gas surrounding the terminals sufficiently to support an electric arc therebetween. The heat thus generated causes the thermostat 8 to operate and move the electrode connected thereto away from the opposite electrode to establish the proper arcing distance between the terminals 4 and 6. This movement of the thermostat also causes the contact 13 to move away from contact 12 and break the circuit through the shunt around the terminals formed by wire 10, contacts 12 and 13, and wire 11, so that, the arc having been established, the entire current flows between the terminals 4 and 6, as will be understood. When the current is turned off, the thermostat immediately resumes its normal position, bringing the contacts 12 and 13 into engagement to re-establish the shunt or by-pass around the terminals 4 and 6.

It will be noted that the refractory wire helix or helixes serve not only as heaters and luminants, but also constitute ballast for the arc and are effective in actuating the thermostat by radiated heat and rendering the terminals 4 and 6 conductive by means of the heat conveyed thereto by the refractory bodies 3 and 5.

In the modification shown in Fig. 2, a resistance is interposed in the shunt or by-pass around the terminals 4 and 6, which resistance is designed to compensate for the voltage of the arc, and is cut out when the contacts 12 and 13 are separated, after the arc has been established. Said resistance is preferably formed of a helix 14 of highly refractory wire, such as tungsten, mounted upon a refractory oxide support 15 and therefore serves as an additional heating element to heat the terminals 4 and 6, to ionize the gas surrounding said terminals and to actuate the thermostat 8. The support 15 is carried by the supporting wires 18 which are fused into the stem of the lamp, while the contact 13 is supported by means of another spud wire 19 carried by the thermostat but which is insulated therefrom.

Although the electrodes are shown separated, it is obvious that they may be normally in contact when no current is flowing in the lamp and will be moved apart to proper arcing distance by the operation of the thermostat when the current is supplied.

The structure disclosed and claimed herein constitutes another embodiment of the invention disclosed in my co-pending application, Serial Number 174,100, filed June 11, 1917, for "electric arc lamps", and said invention is claimed broadly in said co-pending application.

What I claim is:—

1. An arc lamp comprising a container, electrodes therein, at least one of which is formed of a highly refractory non-conducting oxide associated with a highly refractory metallic wire which incandesces at the temperature at which platinum volatilizes and having a terminal formed of a conductor of the second class connected to said wire, a normally closed shunt around said terminal, and means adapted to break the shunt when the terminal is heated sufficiently to become conductive. 85

2. An arc lamp comprising a container, electrodes therein, at least one of which is formed of a highly refractory non-conducting oxide associated with a highly refractory metallic wire which incandesces at the temperature at which platinum volatilizes and having a terminal formed of a conductor of the second class connected to said wire, a normally closed shunt around said terminal, and a thermostat adapted to break the shunt when the terminal is heated sufficiently to become conductive. 90

3. An arc lamp comprising a container, electrodes therein, at least one of which is formed of a highly refractory non-conducting oxide closely surrounded by a helix of highly refractory metallic wire which incandesces at the temperature at which platinum volatilizes and having a terminal formed of a conductor of the second class connected to said wire, a normally closed shunt around said terminal, and a thermostat adapted to move one of said electrodes away from the other and break the shunt when the terminal is heated sufficiently to become conductive. 100

4. An arc lamp comprising a container, electrodes therein, at least one of which is of rod-like form of highly refractory oxide having a helix of highly refractory metallic wire which incandesces at the temperature at which platinum volatilizes closely associated therewith and having a terminal formed of a conductor of the second class connected to said helix, circuit connections, one of which connections includes a thermostat adapted to separate the electrode to proper arcing distance, and a separable shunt around the terminal, which is broken by the separating movement of the electrodes. 115

5. An arc lamp comprising a container, electrodes therein, at least one of which is formed of a highly refractory, non-conducting oxide associated with a refractory metal 130

- wire which incandesces at the temperature at which platinum volatilizes, and having a terminal formed of a conductor of the second class connected to said wire, a normally closed shunt around said terminal, said shunt including a resistance, and means to break the shunt.
6. An arc lamp comprising a base, conductors supported by said base, rod-like electrodes carried by said conductors, one electrode comprising a non-conducting portion, a highly-refractory metal wire associated with said electrode, a second class conductor terminal on said electrode, and circuit connections for said electrodes.
7. An arc lamp comprising a container, electrodes therein, at least one of said electrodes comprising a non-conductive portion of highly-refractory oxide having a terminal formed of a conductor of the second class, a wire of a metal which incandesces at the temperature at which platinum volatilizes associated with said electrode and connected to said terminal, and circuit connections including said wire.
8. An arc lamp comprising a container, electrodes therein, at least one of said electrodes comprising a non-conductive portion of highly-refractory oxide having a terminal formed of a conductor of the second class, a wire of metal which incandesces at the temperature at which platinum volatilizes associated with said electrode and connected to said terminal, circuit connections including said wire, a normally-closed shunt around said terminal, means to break the shunt when the terminal is heated sufficiently to become conductive.
9. An arc lamp comprising a container, electrodes therein, each electrode comprising a non-conductive portion of highly-refractory oxide having a terminal formed of a conductor of the second class, a wire of metal which incandesces at the temperature at which platinum volatilizes coiled about each body and connected to its terminal, and circuit connections including said wires.
10. An arc lamp comprising a container, electrodes therein, each electrode comprising a non-conductive portion of highly-refractory oxide having a terminal formed of a conductor of the second class, a wire of metal which incandesces at the temperature at which platinum volatilizes coiled about each body and connected to its terminal, circuit connections including said wires, a normally-closed shunt around said terminals, and means to break the shunt when the terminals are heated sufficiently to become conductive.
11. An arc lamp comprising a container, electrodes therein, each electrode comprising a non-conductive portion of highly-refractory oxide having a terminal formed of a conductor of the second class, a wire of metal which incandesces at the temperature at which platinum volatilizes coiled about each body and connected to its terminal, circuit connections including said wires, a normally-closed shunt around said terminals, said shunt including a resistance, and means to break the shunt when the terminals are heated sufficiently to become conductive.
12. An arc lamp comprising a container, electrodes therein, each electrode comprising a non-conductive portion of highly-refractory oxide having a terminal formed of a conductor of the second class, a wire of metal which incandesces at the temperature at which platinum volatilizes coiled about each body and connected to its terminal, circuit connections including said wires, a normally-closed shunt around said terminals, said shunt including a metallic wire coiled about a non-conductive core of highly refractory oxide, and means to break the shunt when the terminals are heated sufficiently to become conductive.

In testimony whereof I affix my signature.
JOHN ALLEN HEANY.
